CROSS ARM FOR ELECTRIC TRANSMISSION POLE

Arthur L. Scott, Columbia, S.C., assignor to
C/P Corporation, Newberry, S.C.

Filed Jan. 7, 1970, Ser. No. 20,803

Term of patent 14 years

Int. Cl. D13—03

U.S. Cl. D26—12

FIG. 1 is a front elevational view of a cross arm for electric transmission pole showing my new design;

FIG. 2 is a top plan view thereof;

FIG. 3 is a side elevational view thereof;

FIG. 4 is a cross-sectional view taken on line 4—4 of FIG. 1; and

FIG. 5 is a cross-sectional view taken on line 5—5 of FIG. 1.

I claim:

The ornamental design for a cross arm for electric transmission pole, as shown and described.
